US00D813290S

(12) United States Design Patent **(10) Patent No.:** **US D813,290 S**
Song **(45) Date of Patent:** **** Mar. 20, 2018**

(54) CAMERA

(71) Applicant: **Xiaoyi Technology Co., Ltd.**, Shanghai (CN)

(72) Inventor: **Ye Song**, Shanghai (CN)

(73) Assignee: **SHANGHAI XIAOYI TECHNOLOGY CO., LTD.**, Shanghai (CN)

(**) Term: **15 Years**

(21) Appl. No.: **29/569,781**

(22) Filed: **Jun. 30, 2016**

(30) Foreign Application Priority Data

Jun. 14, 2016 (CN) 2016 3 0237909

(51) LOC (11) Cl. **16-01**

(57) CLAIM

The ornamental design for a camera, as shown and described.

DESCRIPTION

FIG. 1 is a top, front, right perspective view of a camera, showing my new design;

FIG. 2 is a top, rear, left perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines of even length shown in the drawings illustrate portions of the camera that form no part of the claimed design.

1 Claim, 8 Drawing Sheets
